UNITED STATES PATENT OFFICE.

WILLIAM G. ROSS AND OSCAR ONSRUD, OF CHICAGO, ILLINOIS.

TURBINE.

1,244,247.

Specification of Letters Patent. Patented Oct. 23, 1917.

Application filed April 13, 1914. Serial No. 831,613.

To all whom it may concern:

Be it known that we, WILLIAM G. Ross and OSCAR ONSRUD, citizens of the United States of America, and residents of Chicago, county of Cook, and State of Illinois, have invented certain new and useful Improvements in Turbines, of which the following is a specification.

This invention relates to rotary engines or turbines, particularly steam turbines, and one of the principal objects of the invention is to provide an improved construction of disk rotors. Another object of the invention is to provide an improved rotor having a plurality of series of buckets or impact surfaces suitably formed to be acted upon by the fluid in its various stages, and to provide a rotor having a plurality of sets of buckets or impact surfaces with governing devices for automatically opening or closing ports for admitting fluid to one or more of said series, as determined by the velocity and load of the rotor. A further object of the invention is to provide an improved means for super-heating steam between its leaving and re-entering the rotor.

An illustrative embodiment of this invention is shown in the accompanying drawings, in which—

30 Figure 1 is a fragmentary sectional view of the turbine.

Fig. 2 is an enlarged sectional detail of part of the rotor showing the manner of drilling apertures therethrough, for the purpose of providing suitable impact surfaces.

Fig. 3 is a front view of the turbine partly broken away showing the relative arrangement of rotor, reaction elements and super-heating coils.

Fig. 4 is a detail of the rotor and coöperating elements in transverse section.

Fig. 5 is a fragmentary detail in side elevation of one of the end plates or reaction elements.

Fig. 5^a is a sectional view taken on the line A—A of Fig. 5.

Fig. 6 is a sectional detail showing the relative arrangement of the principal parts of the turbine.

Fig. 7 is a left side elevation of a governor and valve operating mechanism.

Fig. 8 is a right side elevation of the gov-

ernor and valve operating mechanism controlled thereby.

Fig. 9 is a perspective view of the assembled machine.

Fig. 10 is a detail of a superheating coil and shows the course of the steam around it.

Referring to Fig. 1 of the drawings, the 60 rotor 1 is fast to a shaft 2, to which devices to be driven may be connected. The rotor 1 is surrounded by a casing consisting mainly of two parts 3 and 4, fastened together by an annular series of bolts 5. The 65 part 4 of the casing is grooved to provide a pair of steam inlet channels 6 and 7, closed by a ring 8, and secured to part 4 by bolts 9. The shaft 2 is journaled in hubs 10 and 11 and having brackets 12 whereby they are 70 made rigid with the parts 3 and 4 of the casing through bolts 13. Live steam is admitted to the channels 6 and 7 through a valve 14 and short pipe 15, Fig. 7. From the channels 6 and 7 it travels through 75 passages 16 and 17 to suitable nozzles 18 and 19 in a side plate 20, secured to the part 4 of the casing. A similar side plate 21 is secured to the part 3 of the casing on the opposite side of the rotor. The latter side 80 plate is also provided with nozzles 22 and 23 and each of the side plates has a series of apertures 24 suitably formed to react on the steam passing through perforations or buckets 25 in the rotor. The latter apertures are suitably formed to coöperate with the different series of nozzles 18, 19, 22 and 23 for the purpose of effecting rotation of the rotor 1 when steam is ejected from the nozzles. The nozzles as shown in Fig. 4 are 90 restricted in cross-section at one point in order that the expansion of the steam when leaving the nozzles may be utilized as usual, to increase the velocity of the steam when entering the comparatively larger apertures 95 25 of the rotor.

The parts 3 and 4 of the casing are each provided with a plurality of annular channels 26, each of which carries a heating coil 27 so located in its respective channel that 100 steam leaving a set of apertures in the rotor 1, in passing through one of the side plates 20 or 21 will take a helical course, as indicated by arrow 57 in Fig. 10, around one of the heating coils 27 in its passage to another series of nozzles in the side plates, the

device shown being a radial type of turbine preferably with the steam traveling from the center out in a wavy path through the rotor. The heating coils 27 are provided with projections 58 extending helically around the coils for the purpose of assisting in properly directing the actuating fluid.

The steam for superheating is admitted and exhausted from the heating coils 27 by connecting pipes 28 passing through hubs 29 in the casing 3 and threaded pipes 30 in apertures in casing 4. Suitable stuffing boxes 31 are also provided to prevent the escape of steam from the annular channels in which the heating coils 27 are located. The apertures 25 in rotor 1, and also the apertures 24 in the side plates are drilled in the manner shown in Fig. 2. Straight transverse holes are first drilled as indicated by drill 32 in Fig. 2. The second and third operations are performed by drills or reamers 33 and 34, having rounded ends and disposed at any desired angle to the rotor or reaction side plates operated upon.

By making the apertures in the manner described, it is possible to obtain any desired impact or reaction surface in solid disks such as shown in the drawings, the drill holes from opposite sides of the disks being made to meet at any desired point and angle, thus modifying the curvature of the impact or reaction surface as desired.

The jets of steam strike the surface 35 after passing or being passed by the knife edge 36. The opposite side 37 of the opening is preferably cut away as shown so as to offer little reaction surface on which the steam may rebound. It may also be noted that, considering the upper side of the aperture in Fig. 2 as the point of entrance of the steam, the aperture is increased in cross-section farther in from the point of entrance.

The rotor 1 as shown in the drawings has two sets of series of annular apertures through which the active steam passes to drive the rotor, the sets being independent of each other, in that different steam is employed in each set. The device is therefore equivalent to engines connected in tandem, it being a complete and operative structure if only one of the sets of rotor apertures is made use of. The series of apertures in each set in the rotor vary in number or diameter, for the purpose of taking care of expansion of the steam.

As shown in Fig. 3, each set of apertures consists of four annular series, spaced about the same distance apart, but each series increasing in number according to their distance radially of shaft 2. The steam leaving nozzles 18 and 19 passes through a single row of apertures 25, then through side plate 21 and around one of the heating coils 27 and back through the next outer row of

apertures 25 in the rotor. It then again passes around one of the heating coils 27 through double sets of nozzles 38 in the side plate 20, and next through the outer double series of apertures 25, which, as shown in the drawings, are slightly less in diameter than the inner rows of apertures but have a combined area which is considerably greater.

The steam finally passes through openings in side plate 21 into an annular exhaust chamber 39 formed in casing 3, and leaves the machine through an opening at 40 communicating with the chamber 39.

The reaction buckets or apertures 24 in the side plates 20 and 21 are formed in about the same manner as the impact buckets 25 in the rotor as shown in Figs. 4, 5, and 5^a. It is preferred to cut away the inactive edges 41 of the apertures and also to channel the side plates along the line of each series of apertures as indicated by the numeral 42. This is done for the purpose of lessening resistance due to rebound of steam when entering the reaction buckets 24.

The rotor shaft 2 carries a governor 43 constructed to shift a rod 44 upwardly as the speed of shaft 2 increases. The specific construction of governor is not shown in the drawings, but the rod 44 when moved upwardly engages the end of a screw 45 carried by a bell crank lever 46. The bell crank lever is pivoted on a pin 47 in a brace 48 extending rearwardly from the journal 11 for shaft 2. The bell crank lever 46 has two horizontally disposed arms 49 and 50. The arm 49 controls valve 14 for admitting steam through pipe 15 to the annular steam chest 6. The valve is normally open but as the speed of the rotor increases over some predetermined rate, the valve is gradually moved toward its closed position by movement of bell crank lever 46 through the action of the rod 44 in the governor. The arm 50 of the bell crank lever carries an adjustable member 51, having a pair of rollers 52 through which extends a lever 53 supported by a fixed pivot 54 and extending inwardly of said pivot below a valve stem 55 of a valve 56. Valve 56 is also normally wide open, but when the bell crank lever 46 is rocked by action pin 44, the valve is permitted to move toward its closed position. By adjusting the member 51 along the arm 50 and lever 53, the mechanism may be regulated to cause the valve to close after a slight movement of the rod 44 or a comparatively great movement of the rod. The valve controlling mechanism is arranged so that when the rotor arrives at a certain predetermined speed, valve 56 will be closed, shutting off steam to the steam chest 7, making the inner set of buckets 25 of the rotor entirely inactive, the continued drive of the rotor being effected by the outer set of buckets fed from the steam chest 6.

If the rotor still con-

tinues to rotate up to the point where further action of governor 43 takes place, the valve 14 is closed sufficiently to permit the passage of steam into the chest 6 only sufficient to maintain the desired rotation.

In the operation of the device, the valves 14 and 56 are normally open, and steam admitted to the machine is free to pass into the steam chests 6 and 7 and from there it is projected through the nozzles 19 and 18 into the buckets 25, forming the innermost series of each set of buckets. From these series of buckets, the steam passes through the reaction buckets 24 in side plate 21 around the super-heating coils 27 and back through the nozzles 22 and 23 into the second series of rotor buckets. It again passes through the reaction buckets in the side plate 20 and around super-heating coils, and finally through the two outer rows of nozzles in each set, into the two outer rows of buckets, and each set of buckets of the rotor, the steam leaving the apparatus from chamber 39 through the opening 40. When the rotor has obtained a velocity sufficient to cause the governor to shift rod 44 outwardly, the bell crank lever 46 is rocked to operate valve 56 and shut off steam from the steam chest 7 and the inner set of rotor buckets. If the speed of the rotor is further increased through the action of the steam on the outer set of buckets alone, the valve 14 is gradually moved toward its closed position, maintaining the desired speed of the rotor.

Although but one specific embodiment of this invention has been herein shown and described, it will be understood that numerous details of the construction shown may be altered or omitted without departing from the spirit of this invention as shown by the following claims.

We claim—

1. In a rotary engine, the combination of a disk-shaped rotor having a plurality of rows of annular perforations, a governor, and means controlled by said governor for

preventing fluid from passing through one or more of said rows of perforations.

2. In a rotary engine, the combination of a disk-shaped rotor having a plurality of sets of annular rows of perforations, means for directing fluid through each set of perforations from one row to another, and a governor having connections for preventing fluid from passing through one of said sets of perforations.

3. In a rotary engine, the combination of a disk-shaped rotor having a plurality of rows of perforations through which fluid passes by the action of driving said rotor, means for directing the fluid from one row of perforations to another, a casing surrounding said rotor and having annular grooves located in position to receive fluid from one row of perforations, and permitting it to pass through another row of perforations, and super-heating coils so located in said annular grooves that the fluid entering said channels will pass around the coils before leaving said channels.

4. In a turbine, the combination of a casing, a rotor having a plurality of impact surfaces and a channel in said casing for conducting an actuating fluid from one impact surface to another, a super-heating element in said channel, said super-heating element having a projection extending helically around said element.

5. In a turbine, a rotor comprising a single disk having an annular row of holes therein, a nozzle located at one side of said disk for directing fluid under pressure into said holes, said holes being formed to provide an enlarged pocket inward of the inlet and outlet ends thereof.

Signed at Chicago this 10th day of April 1914.
